CABINET WITH BRACKET LIGHTS

George E. Eckert, Fort Atkinson, Wis., assignor
to Moe Brothers Manufacturing Company, Fort
Atkinson, Wis., a corporation of Wisconsin

Application December 23, 1949, Serial No. 6,795

Term of patent 14 years

(Cl. D4—3)

To all whom it may concern:

Be it known that I, George E. Eckert, a citizen of the United States, residing at Fort Atkinson, in the county of Jefferson, and State of Wisconsin, have invented a new, original, and ornamental Design for a Cabinet with Bracket Lights, of which the following is a specification, reference being had to the accompanying drawing, forming part thereof.

Fig. 1 is a view in front elevation showing a cabinet with bracket lights embodying my new design.

Fig. 2 is a view in side elevation showing the cabinet with bracket lights illustrated in Fig. 1.

Fig. 3 is a plan view showing my new design.

Fig. 4 is a view taken in cross section on the line 4—4 of Fig. 1.

I claim:

The ornamental design for a cabinet with bracket lights, as shown.

GEORGE E. ECKERT.
